UNITED STATES PATENT OFFICE.

JOSEPH M. HOFFMAN, OF BROOKLYN, NEW YORK, ASSIGNOR OF ONE-HALF TO JOHN F. NELSON, OF BROOKLYN, NEW YORK.

ANTISLIPPING REMOVABLE SOLE FOR SHOES.

No. 818,173.

Specification of Letters Patent.

Patented April 17, 1906.

Application filed April 18, 1905. Serial No. 266,282.

To all whom it may concern:

Be it known that I, JOSEPH M. HOFFMAN, a citizen of the United States, residing in the city of Brooklyn, State of New York, have 5 invented certain new and useful Improvements in Antislipping Removable Soles for Shoes, of which the following is a full, clear, and exact description, reference being had to the accompanying drawings, forming a part 10 of this specification.

My invention relates generally to removable soles for shoes for the purpose of preventing slipping and specifically to removable rubber sole-pieces with which is combined means to positively clamp the removable sole to the shoe during use. The improved device I have invented is especially applicable to prevent slipping by tenpin bowlers when delivering a ball on the polished wooden floor.

My invention has for its object to provide a rubber sole with a frictional tread or under face extending under the ball of the foot only—that is to say, back to the shank—25 with a cap-like front to adapt it to be held in place over the toe and forward part of the sole and with mechanical means embedded in the rubber by molding or otherwise to enable the rear portion of my removable rubber 30 sole to be positively held when in use by a clamping action against the sole of the shoe of the wearer.

To these ends my invention consists of the device which accomplishes these objects, 35 hereinbefore described, the novel features of which both elementally and in combination will be now fully described, and finally pointed out in the claims.

In the accompanying drawings, illustrating 40 my new device, Figure 1 is a plan view of my removable sole, parts of the under surface being shown in dotted lines. Fig. 2 is a side elevation of the same in place on the shoe of the wearer, and Fig. 3 is a transverse 45 vertical section on the line 3-3 of Fig. 1.

As before stated, my improved device is designed more particularly for use of tenpin bowlers, where slipping of the foot on the floor in delivering a ball is very common. 50 To prevent such slipping, it is now common with bowlers to use ordinary rubber or tennis shoes, which are heavy, cumbersome, and expensive. For that and analogous uses to which it is applicable my device is light in

weight, inexpensive, and is adapted to quick 55 and convenient attachment to and detachment from the shoe of the wearer, but in such manner that while in use the device will be fixedly but removably clamped to the shoe of the bowler or wearer.

The device is made, preferably, of rubber such as men's rubber overshoes are usually made of, but with a slightly-thicker sole or tread portion A for the purpose hereinafter mentioned. It is provided with a toe-cap or 65 front sole-flange B, and the tread portion extends rearward to a point about coincident with the shank of the shoe, as seen in Fig. 1, in order that the clamping device may be more suitably adjusted and be more effect- 70 ily operative. The tread portion A' (see Fig. 2) is provided with a roughened under surface, preferably a corrugated surface, as indicated at d, of the kind common with some sorts of sporting or field shoes for the 75 purpose of increasing frictional hold on the floor when the device is in use by the wearer. Near the rear end of this tread portion and transversely thereto is embedded in the rubber a metal keeper D, consisting of thin 80 sheet metal stamped out to provide two channels s and t, one for the bar or body F of the clip C to slide in and the other serving as a pocket for the locking-pawls E with their springs E'. This keeper is provided also 85 with an extension or tongue D' to hold the rearward channeled body of the keeper more securely against movement in the rubber and also to give the requisite form to and serve as a stiffener for the tread portion or 90 sole proper of the device.

In the groove s of the keeper D is inserted on each side a flat bar F, fitting reasonably snug in said groove, but capable of being readily slid longitudinally therein, said bar 95 carrying on its outer end a curved clip C and having on its rearward longitudinal edge a series of serrations C', forming a pawl-rack. The partition-wall n between the grooves or channels s and t in the keeper D has on each 100 side of its central line an opening r, through which a projection D², operating as a pawl, projects, and also another contiguous opening r', in which a pivot-pin or projection e projects, said projections D² and e being on 105 the upper and inner end of a pawl-bar D³, back of which or forming the inner end thereof and resting on one wall of the groove t is

- a flat spring E', curved to force the pawl D² into the rack on the edge of the clip-bar F. The pin or projection e enters the opening r' in the partition-wall between the grooves.
- 5 The pawl-bar D² is prevented from dropping out, being held in place by the pivot-pin e, and said bar has an operating end E, which projects beyond the face of the groove t, by which the bar can be pivotally moved to detach the pawl from operative register with the rack-bar.

10 The provision of oppositely-disposed movable clips, each constructed with a rack edge and each coacting with a separately-movable 15 spring-actuated pawl, enables the rubber sole to be readily clamped to the edges of the shoe-sole and as readily detached therefrom; but it also provides a reasonable amount of 20 adjustment for attaching the device to shoe- soles of somewhat varying widths. The parts are shown in clamped or locked position in Fig. 1.

To remove the device from the shoe, the projecting end of the pawl-bar is pushed to 25 swing it pivotally on the pin e and depress the spring E' and disengage the locking-pawl D² from engagement with the clip-bar rack C', then push or swing the sole in the direction of the other clip, for it is obviously unnecessary to unlock both. To attach the device to the sole of the shoe, the toe-piece is first slipped on the foot, the tread portion A' 30 adjusted centrally on the shoe-sole, with one clip in position embracing one side of the shoe-sole at the shank thereof, then pushing in the other clip-bar in its groove in the keeper as far as it will go, drawing the rubber sole toward the heel of the shoe, and the rack and pawl will automatically engage in locked 35 position.

Having thus described my invention, I claim as new and desire to secure by Letters Patent—

40 1. A removable antislipping sole for shoes, consisting of the combination with a sole-piece having a toe-cap and a tread-surface adapted to coincide with the shoe-sole rearward to the shank thereof, of a longitudi-

nally-grooved metallic bar mounted fixedly on the sole-piece contiguous to the rear end thereof and transversely thereto, a pair of oppositely-disposed clip-carrying rack-bars adapted to slide independently in said grooved bar, with pawl mechanism operating to respectively lock and release each of said 55 clip-carrying bars in the said grooved bar.

2. In a device of the character recited, the combination of the following elements; a sole-piece having a toe-cap and a tread-surface adapted to coincide with a shoe-sole rearward to the shank thereof, with means to removably clamp it to the shoe-sole, consisting of a grooved metallic keeper-bar mounted fixedly on the sole-piece contiguous to the rear end thereof and transversely thereto, a 60 pair of oppositely-disposed and independently-movable clip-carrying bars provided with a serrated edge and adapted to slide in the groove of the keeper-bar, with means to respectively lock and release each clip-carrying bar therein, consisting of a pawl-carrying and spring-actuated bar also mounted in the 65 grooved keeper-bar and projecting outwardly beyond the edge thereof.

3. In a device of the character recited, the combination with a sole-piece of thick rubber in the tread portion, having a toe-cap and a frictional tread-surface, of a metallic keeper embedded in the rubber, said keeper having a forward-extending tongue and a body portion with two contiguous grooves therein separated from each by a slotted partition, a pair of clip-carrying bars having a serrated edge and mounted slidably in one of said 80 grooves, and a spring-actuated pawl-carrying 85 bar mounted slidably in the other of said grooves, the pawl extending through the slot in the said partition and normally registering with the serrated edge of the clip-bar.

In testimony whereof I have hereunto affixed my signature this 15th day of April, A. D. 1905.

JOSEPH M. HOFFMAN.
